UNITED STATES PATENT OFFICE

WILLIAM MITCHELL, OF PONCA CITY, OKLAHOMA, AND ALBERT H. LOUCKS, OF MARION, INDIANA, ASSIGNORS TO MARION MACHINE FOUNDRY & SUPPLY COMPANY, OF MARION, INDIANA, A CORPORATION

PITMAN

Application filed October 3, 1927. Serial No. 223,802.

This invention relates to a pitman construction peculiarly adapted for use in oil and other well drilling machines and particularly between the walking beam and power crank 5 shaft.

The object of this invention is to make a steel pitman suitable for practical use in the oil field and provided with novel arrangement of the pivoted bearings whereby the 10 bearings are kept in perfect alignment with the wrist pin so as not to have a tendency to bend the wrist pin or to put undue pressure on a small area of the bearings.

The deep well drilling, with a corresponding heavy load on the pitman, necessitates the use of a steel pitman, and the usual steel pitman has rigid bearings for the wrist pin, and since the machinery of a drilling rig is not accurately lined up, the pitman is usually out 20 of line with the pin especially when under load, and has this position when the load is reduced, as on the downward stroke of the tools. This has a tendency to bend the wrist pin and finally break it. Also it causes the 25 bearings to heat excessively and cut the bearing metal and also score the wrist pin.

The object of this invention is to overcome the foregoing trouble and the chief feature of the invention for accomplishing said object 30 consists in the provision of a pivoted bearing which is free to oscillate in the pitman and which permits the bearing to be in proper alignment with the wrist pin at all times.

The full nature of the invention will be understood from the accompanying drawings and the following description and claims:

In the drawings Fig. 1 is a side elevation of the pitman constituting this invention and parts associated therewith, said parts being 40 partly broken away. Fig. 2 is an enlarged perspective view of the lower portion of the pitman shown in Fig. 1 with the parts arranged in working position. Fig. 3 is a view similar to that shown in Fig. 2 with the parts 45 of the pitman in their positions during removal from the wrist pin or when not on the wrist pin.

Fig. 4 is a central vertical section through the portion of the pitman as shown in Fig. 2. Fig. 5 is a central vertical section of the por-

tion of the pitman as shown in Fig. 3. Fig. 6 is an elevation of a part of the pitman with the lower bearing being removed, and other parts omitted.

There is shown herein an end of a walking beam 10 of the usual form found in drilling rigs for oil wells. It is operatively connected by the pitman 11 with the wrist pin 12 adjustably mounted on the crank 13 of the shaft 14. The crank shaft 14 is mounted in 60 bearings 15 on supports 16 extending up from beam 17. The power is thus transmitted through the pitman from crank shaft 14 to the walking beam for the purpose of operating the latter.

The pitman includes a bar in the form of an I-beam 20 to the upper end of which there is secured a stirrup 21 which extends over the end of the walking beam and is secured in operating connection therewith by the usual 70 means.

To the lower end of the bar 20 there is secured a yoke 25 in which the bearing of the pitman is mounted. This yoke is a U-shaped plate having in one side a slot 26 and in the 75 other side and opposite the lower portion of the slot 26 there is a hole 27. The slot 26 and hole 27 receive the gudgeons 28 and 29 respectively, of the lower bearing member 30 for the wrist pin 12. These gudgeons are 80 round and extend transversely of the wrist pin so as to permit rocking movement to the bearing member 30, and an oil cup 31 is removably secured to the gudgeon 28.

The upper bearing member or cap 32 is 85 mounted on the lower end of the rod 33 by means of a plate 34. Said rod extends through an opening 35 into plate 34 and has on it a semi-spherical head 36 which lies and operates in a chamber 37 in the upper part 90 of the bearing member 32, as indicated in Figs. 4 and 5. The spherical surface of said head engages the upper bearing member at the lower wall or surface of the chamber 30, as shown in Fig. 4 and rocks thereon during 95 any oscillation of the rod 33. The upper surface of the head 36 is bevelled away so as to make the head slightly less than semi-spherical and thereby permit the rocking movement of the chamber head in the chamber 30 and 100

yet hold the head snugly between the upper plate 34 and the lower wall 37 of the bearing 33 so that there will be no loss of power or play between the bearing and the rod 33.

5 The rod 33 is threaded at its upper end into an eccentric strap 40. Therefore, the unit composed of the rod 33 and the eccentric strap 40 is adjustable in length and it is pivotally mounted on an eccentric 41 that is mounted on a pin 42 in a yoke 43 originally secured to the I-beam 20. A hand lever 44 is rigidly secured to the eccentric 41 and the eccentric is so arranged that when said hand lever is turned downward against the I-beam, as shown in Figs. 2 and 4, the eccentric would force the rod 33 downward and through it, the cap bearing member 32 would be forced downward to close the bearings on the wrist pin, as shown in Fig. 1, and this is the condition during operation of the machine.

10 When it is desired to remove the pitman from the wrist pin, the hand lever 44 is turned upward to the position shown in Figs. 3 and 5 which would cause the eccentric to raise the rod 33 and not only release the cap bearing 32 but lift it away from the lower bearing member, as shown in Fig. 3 which would enable the pitman to be moved laterally off of and away from the wrist pin.

15 30 Since the rod 33, which may be called the bearing controlling rod, is such that its length can be adjusted, it is so adjusted that, when the hand lever is down in the position shown in Figs. 2 and 4, the top bearing member 33 will be held tightly in place and will be able to resist the upper thrust without any displacement.

20 35 By reason of the slot 26 the lower bearing member 30 can be easily tilted out of its seat and entirely removed if desired and a new one replaced in its stead. Rod 33 is guided accurately by a plate 50 which has centrally in it a hole 51 that fits the rod so as to permit its slight oscillatory movement, as seen in Figs. 3 and 4, and yet hold it rather closely in position. Said plate 50 has two lateral holes 52 in registry with the nuts 53 so that they will not strike the plate 50. There are handles 54 and 55 on the frame. There is also a strap 56 at the bottom for the purpose of supporting the handle 55 and strengthening the sides of bearing yoke 25.

40 45 It is evident from the foregoing explanation that the bearing for the wrist pin may rock or oscillate to accommodate it to position of the wrist pin and to be in proper alignment therewith. This is desirable because the wrist pin is not always horizontal but varies to different slight degrees from the horizontal position and the chief object of the invention is to enable the bearing to accommodate itself to the different positions of the wrist pin so as to enable the wrist pin to bear equally on the surfaces of the bearing and always maintain the desired alignment.

50 It is also seen that there is a very convenient and quickly operated means for releasing the bearing members and removing the pitman from the wrist pin, and also the lower bearing member is readily removable from the wrist pin.

55 The invention claimed is:

1. A pitman including a bar with a yoke secured thereto, said yoke having bearing openings in the opposite sides thereof, a main wrist pin bearing member having round gudgeons on the opposite ends thereof and extending transversely of the wrist pin and fitting in said openings, a companion bearing member in said yoke, and means for holding said companion bearing member against said main bearing member, said means being loosely connected with said companion member so that the main bearing member may rock to accommodate itself to the wrist pin.
